UNITED STATES PATENT OFFICE

132,286

DESIGN FOR A NECKTIE HOLDER

Leo Soukup and Richard V. Westover,
Lincoln, Nebr.

Application September 15, 1941, Serial No. 103,358

Term of patent 14 years

To all whom it may concern:

Be it known that we, Leo Soukup and Richard V. Westover, citizens of the United States, residing in Lincoln, in the county of Lancaster and State of Nebraska, have invented a new, original, and ornamental Design for a Necktie Holder, of which the following is a specification, reference being had to the accompanying drawing, forming part thereof.

We claim:

The ornamental design for a necktie holder, as shown.

LEO SOUKUP.
RICHARD V. WESTOVER.
